UNITED STATES PATENT OFFICE.

JOHN J. JAKOSKY, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA.

APPARATUS FOR ELECTRICAL SOUND REPRODUCTION.

Application filed July 23, 1926. Serial No. 124,396.

This invention relates to apparatus for the electrical reproduction and amplification of sound from a phonograph record, and the main object of the invention is to improve the quality of such reproduction and particularly to eliminate substantially entirely the scratching noise resulting from the passage of the needle or stylus over the record.

In the mechanical reproduction of sound from phonograph records one of the principal objections has been the constant scratching noise which was produced due to vibrations of extremely high frequency imparted to the phonograph stylus by the inherent roughness or irregularity of the surface of the record. It has recently been found that by means of electrical reproduction this scratching noise may be largely reduced, and the quality of reproduction greatly improved. I have found, however, that in the means heretofore proposed for the electrical reproduction and amplification of sound from a phonograph record, the scratching noise is not entirely eliminated and I have found further that the scratching noise which is otherwise present in electrical reproduction may be substantially eliminated by placing a by-pass condenser of suitable capacity at a suitable point in the circuit, for example directly across the terminals of the secondary winding of one of the transformers used for amplification, and preferably the last transformer in the circuit. I have further found that when it is desired to utilize the same amplifying system alternatively in conjunction either with a radio receiving set or with an electrical phonograph reproducer, the inclusion of such a by-pass condenser of said suitable value at the point mentioned is undesirable for use in conjunction with the radio receiving set, and it is therefore desirable to provide means whereby said condenser is connected in the circuit only when the same is used in electrical phonograph reproduction.

My invention comprises not only the inclusion of a by-pass condenser at a suitable point in the circuit as above mentioned, but also includes a suitable switching device whereby such by-pass condenser may be automatically connected in the circuit when the amplifier is to be used in conjunction

with electrical phonograph reproduction and may be automatically disconnected from the circuit when the device is to be used for radio reception.

The accompanying drawings illustrate embodiments of my invention and referring thereto:

Fig. 1 is a wiring diagram showing the application of my invention to an amplifying system adapted for use in connection with either a radio receiving set or an electrical phonograph reproducer.

Fig. 2 is a vertical section of the switching means illustrated diagrammatically in Fig. 1.

Fig. 3 is a wiring diagram showing another modification of the invention in which the switching device is also adapted to disconnect the detector tube of the radio receiving set and insert a compensating resistance when the phonograph reproducer is connected to the amplifying means.

The amplifying system shown in Fig. 1 comprises two amplifying transformers 1 and 2 and two thermionic tubes 3 and 4 each provided with grid 5, filament 6, and plate 7. Said parts are provided with the usual A, B, and C battery connections as shown. The secondary winding of transformer 1 is connected in the grid circuit of thermionic tube 3, while the plate of such tube is connected to the primary winding of transformer 2. The secondary of transformer 2 is connected to the grid circuit of thermionic tube 4 whose plate is connected to an electrical sound producing or loud speaking device indicated at 10.

In the drawings I have shown the amplifying system above described as forming part of a radio receiving set but it will be understood that the phase of my invention which relates solely to the inclusion of a by-pass condenser in shunt across the secondary winding of an amplifier transformer, and preferably of the last transformer, is applicable in connection with any electrical amplifying means whether the same be connected to a radio receiving set or whether it be a separate unit or whether it be intended solely for use in connection with electrical phonograph reproduction.

The radio receiving set illustrated in Fig. 1 also comprises a thermionic detector tube

12 having grid 13, filament 14, and plate 15. The system further comprises antenna 16, ground connection 17, primary and secondary coils 18 and 19, condenser 20, variable condenser 21 and gridleak and condenser 22. The detector 12 is also provided with the usual A and B battery connections as shown.

My invention may be applied in connection with any suitable means of electrical phonograph reproduction, such means comprising essentially a device which is adapted to produce electrical impulses corresponding in frequency and intensity to the undulations of the phonograph record and said device being connected to the input of an electrical amplifying system. In Fig. 1 I have illustrated diagrammatically one type of means for producing electrical impulses as above described, such means comprising a needle-carrying member 25 adapted to hold a phonograph needle indicated at 26 and secured to a lever member or rocking member 27 mounted to rock between rubber pads indicated at 28 and 29. Lever member 27 is connected at one side of the axis about which it rocks to a translating member such as wire 30 whose other end is connected to one end of armature 31 which is mounted in any suitable manner to rock about an axis extending through its midpoint 32 and perpendicular to the plane of the drawing. A permanent magnet 33 is provided with pole pieces 34 and 35 at the respective sides of armature 31 so that when said armature rocks between said pole pieces the magnetic flux therethrough varies in direction and intensity. An electrical coil 36 is provided around armature 31, said coil being either adapted to rock with the armature or being mounted in stationary position surrounding the same. The above described device forms no essential part of this invention but is more fully described and claimed in my copending application Ser. No. 102,100, filed April 15, 1926.

The output terminals of the above described device, or of any other suitable device for producing electrical impulses corresponding to the undulations of a phonograph record, may be connected in any suitable manner to the input of an electrical amplifying system for example to the terminals of the primary winding of transformer 1. For the purpose of my invention, and in any case when it is desired to permit utilization of a single amplifying system alternatively in conjunction with radio reception or electrical reproduction, I prefer to provide detachable connecting means between the reproducer and the amplifier. For example the ends of coil 36 may be connected by wires 40 and 41 to the contact portions 42 and 43 respectively of contact plug 44 which is adapted for inser-

tion in a contact jack indicated diagrammatically at 45 in Fig. 1 and shown more in detail in Fig. 2. A suitable rheostat 46 may be inserted in one of the wires 40 or 41 for varying the intensity of current therein and hence varying the volume of sound production.

Referring now to Fig. 2 in conjunction with Fig. 1, the jack 45 may comprise a contact member 48 having a sleeve portion 49 through which plug 44 is adapted for insertion in such manner as to make connection between contact portion 43 and sleeve portion 49. The jack further comprises spring contact 50 whose free end is adapted to make connection with contact portion 42 when the plug is so inserted. The contact members 48 and 50 may be connected respectively to binding posts 51 and 52 whence wires 53 and 54 lead to the terminals of the primary winding of transformer 1. Jack 45 is also provided with a pair of spring contacts 57 and 58, the lower one of which is adapted to be raised, as by means of insulating pin 59, when the contact spring 50 is raised by insertion of the connecting plug as above described, so as to make connection at 60 between contact members 57 and 58. Contact member 57 is connected to binding post 62 and contact member 58 is connected to a condenser 63 of any suitable type and of sufficient capacity to substantially by-pass all current impulses of higher frequency than the sounds which are intended to be reproduced. Condenser 63 is in turn connected to binding post 64. Binding posts 62 and 64 may be connected respectively by wires 65 and 66 to the two terminals of the secondary winding of transformer 2.

The jack 45 may if desired be mounted in a suitable casing 67 having one end formed as an insulating base 68 on which are mounted the binding posts 51, 52, 62, and 64. Sleeve portion 49 may be externally threaded and may be provided with a nut 69 so as to permit mounting of the jack on the panel of a radio receiving set or an amplifier, in the usual manner of such devices. Contact member 48 may be formed as a supporting base for the jack in the usual manner of such devices, the other contact members being mounted thereon by means of screws 55 and separated from one another by insulating spacers 56.

In Fig. 1 the parts of the circuit which are utilized only in the operation of the circuit for radio purposes are shown in dotted lines, while the parts of the amplifying system, which are used both for radio reception and phonographic reproduction, are shown in light solid lines. The parts which are added to the circuit for the purposes of my invention as shown in heavy solid lines so as to more clearly differentiate these parts from the parts of the standard circuit. It

will of course be understood that my invention is not limited to any particular type of amplifying system as it may be applied in connection with any ordinary thermionic tube amplifier.

The operation of the apparatus and circuits above described is as follows:

When it is desired to use the circuit for radio reception the plug 44 is removed from jack 45 thus breaking connection between the electrical phonograph reproducer and the amplifying system, and also disconnecting condenser 63 from the circuit. The circuit then operates in the normal manner of radio receiving circuits. When, however, it is desired to utilize the circuit for electrical phonograph reproduction the radio receiving circuit is detuned as by means of variable condenser 21 so as to prevent radio reception thereby during the phonographic reproduction. Plug 44 is then inserted in jack 45 thus making contact respectively between contact members 42 and 50 and contact members 43 and 48. Electric coil 36 is thus placed in electrical connection with the primary winding of transformer 1 so that when stylus 26 is placed in engagement with the grooves of a phonograph record the electrical impulses set up in said coil corresponding to the undulations of such record are supplied to said transformer and such impulses are amplified in the usual manner of thermionic tube amplification so as to produce, at the loud-speaking or sound producing means 10, sound of the desired intensity and possessing good qualities of clarity and accuracy.

The insertion of plug 44 in jack 45 also causes connection to be closed at 60 between contact members 57 and 58 so that condenser 63 is connected in shunt across the terminals of the secondary winding of transformer 2. The function of such condenser is to by-pass therethrough the electric current impulses of relatively high frequency corresponding to the usual scratching noise produced in phonographic reproduction as above described and said condenser is therefore of such capacity as to by-pass substantially all impulses of such relatively high frequency while permitting substantially no by-passing therethrough of electric current impulses of a frequency equal to that of all sounds within the range of ordinary phonograph reproduction. It has been found that for certain types of amplifying sets a condenser having a capacity of from .001 to .005 microfarads may advantageously be employed for this purpose. The by-passing of such relatively high frequency current impulses through condenser 63 substantially prevents the flow of such high frequency impulses through the grid circuit of thermionic tube 4 so that the amplifying impulses produced in the plate circuit of said tube and

supplied to the loud-speaker 10 are substantially free from such relatively high frequency impulses. The sound produced by loud-speaker 10 is therefore substantially free from sounds of a pitch corresponding to such high frequency impulses and particularly from the scratching noise ordinarily found in phonographic reproduction.

In the form of the invention illustrated in Fig. 3 I have shown a switching device which is adapted to perform not only the functions above described, but also to disconnect the filament of the detector tube 12 from the current supply circuit therefor, and to insert a compensating resistance in series with the filaments of the remaining tubes of the circuit, thus preventing undue deterioration of the filament of the detector tube and also causing the energization of the filaments of the remaining tubes to remain the same as though the detector tube were connected in circuit.

In illustrating this form of the invention the same scheme has been employed as in the other form, that is to say the portions of the normal circuit which are used only in connection with radio reception are shown in light dotted lines while the remaining portions of the normal system are shown in light solid lines, while the parts of the circuit which are added for the purposes of my invention and which are used in connection with electric phonograph reproduction are shown in heavy solid lines. In addition certain wires which are added to the circuit for the purposes of this aspect of my invention and which are employed only in connection with radio reception are shown in heavy dotted lines. The radio receiving set comprises essentially the same parts as shown in Fig. 1 and the switching device also comprises as before contact members 48, 50, 57, and 58, which are connected in the same manner as before and also by-pass condenser 63 connected as before. In this case however the usual wire (indicated at 70 in Fig. 1) for connecting one of the filament terminals of detector tube 12 to the A battery is removed and wires 72 and 73 are substituted therefor. A suitable resistance 74 is connected in the filament circuits of the thermionic tubes 3 and 4, the wire 72 aforesaid being connected at one side of said resistance and another wire 74 being connected at the other side of said resistance. The jack indicated at 45' is provided in this case with additional contact springs 76, 77, and 78 which are so arranged that when plug 44 is inserted in the jack the raising of contact spring 50 lifts an insulating pin 79 off of contact spring 76 which then by its own resilience breaks connection with contacts 77 and 78. When, however, plug 44 is removed from the jack, pin 79 engages contact spring 76 and moves the same into position.

sition to close connection with contact members 77, and 78 and 81 and 82 respectively. The plug 44 is connected by wires 40 and 41 to an electrical phonograph reproducer for 5 example of the same construction as indicated in Fig. 1.

In the operation of this form of the invention the functions of the switching device in connecting the electrical phonograph reproducer to the input of transformer 1 and for connecting by-pass condenser 63 across the output terminals of transformer 2 when plug 44 is inserted in jack 45' are performed in substantially the same manner as above described. It will be observed however that when the plug is so inserted connection is broken between contact member 76 and contact members 77 and 78 so that the filament of detector tube 12 is disconnected from the 10 15 20 A battery circuit. Furthermore resistance 74 is placed in series with the filaments of amplifier tubes 3 and 4, said resistance being of such value that when so inserted the current flow in the filaments of said amplifier tubes is substantially the same as though said resistance were out of the circuit and the filament of the detector tube were connected in the circuit. Therefore when plug 44 is inserted so as to permit operation of the 25 30 35 circuit for phonographic reproduction purposes the filament of the detector tube 12 is not energized and deterioration thereof is prevented, while the filaments of amplifier tubes 3 and 4 are energized or heated to the same intensity as though the detector tube were in circuit.

When, however, plug 44 is removed from jack 45' connection is closed between contact member 76 and contact members 77 and 78 40 and the filament circuit of detector tube 12 is thereby completed through wire 72, contact member 77, contact member 76, contact member 78, and wire 73. The detector tube is thereby energized so as to permit utilization 45 50 55 of the circuit for radio reception purposes. At the same time however a shunt is placed across resistance 74, through wire 72, contact 77, contact 76, and wire 75. It is therefore seen that when the detector tube, as well as the amplifier tubes, are connected to the A battery terminals, resistance 74 is out of the circuit, while when the detector tube is disconnected from the A battery terminals, said resistance is in the circuit, which results in uniform energization of the filaments of the amplifier tubes at all times whether the same are being used in connection with radio

reception or electrical phonograph reproduction.

I claim:

1. An apparatus for electrical sound reproduction, comprising in combination with the amplifying system of a radio receiving apparatus, an electrical phonograph reproducing device, electrical connections between 60 65 70 75 80 85 90 95 100 said reproducing device and the input of said amplifying system, switching means included in said electrical connections for making and breaking connection between the reproducing device and the amplifying system, a condenser, means connecting said condenser in shunt across the secondary terminals of a transformer of said amplifying system, and means for automatically making and breaking the connection between said condenser and said transformer upon operation of said switching means to respectively make and break the connection between the reproducing device and the amplifying system.

2. An apparatus as set forth in claim 1 and comprising in addition an electrical resistance means, and means for automatically disconnecting the filament of the detector tube of the radio receiving and for inserting 85 90 95 100 said resistance in series in the filament circuit of the amplifying system, upon operation of said switching means to make the connection between the reproducing device and the amplifying system.

3. An apparatus for electrical sound reproduction comprising, in combination with an electrical amplifying system whose input is connected to radio signal detecting means, an electrical phonograph reproducing device, an electrical circuit connecting said reproducing device to the input of said amplifying system, a condenser, an electrical circuit connecting said condenser in shunt across the secondary terminals of a transformer of said amplifying system, a switching device including contact means connected in the circuit between the reproducing device and the amplifying system and also including contact means included in 105 110 the condenser circuit and means operatively connecting the respective means so that operation of said switching device to close or open said first named contact means also respectively closes or opens said last-named contact means.

In testimony whereof I have hereunto subscribed my name this 14 day of July, 1926.

JOHN J. JAKOSKY.
